UNITED STATES PATENT OFFICE.

GIUSEPPE F. AZZARA, OF BROOKLYN, NEW YORK.

SHOE SOLE.

Application filed May 5, 1925. Serial No. 28,191.

This invention relates to shoe manufacture and has particular reference to an improvement in an insole for "stitch-down" shoes, namely, a shoe structure in which the edge of the upper is turned outwardly and secured to the outer sole.

At the present time it is the general practice in the manufacture of stitch-down shoes to employ a combined insole and middle sole by cutting a strip of leather to provide the same with a main body formed with a relatively thin marginal flange or welt portion projecting outwardly from and extending completely around the shank and forepart at the lower portion thereof. The body is slotted inwardly from its marginal edge in line with the upper face of the flange or welt portion to receive the lower edge of the lining which is worked into the slit and secured preferably by cement. It is obvious that the working of the edge of the lining into the slit entails a considerable amount of time and labor, precludes a smooth finish and is a generally tedious operation.

It is therefore one of the outstanding objects of the present invention to overcome the above recited difficulty by disposing the slit in these combined insoles and middle soles at an angle and extending the same completely through the lower surface of the body so as to produce an integral flange or welt portion provided with an underlying integral rand portion having a skived upper edge, the confronting under surface of the body of the sole having a complementary skived marginal portion permitting upon flexing a separation of the confronting skived faces of the body and rand portion to facilitate the placing and securing of the edge of the lining therebetween.

The invention furthermore comprehends a shoe sole structure which is comparatively simple, inexpensive and highly efficient in its purpose.

With the above recited and other objects in view, reference is had to the following specification and drawings in which there is exhibited one example or embodiment of the invention which is in no way intended as a limitation upon the scope of the ap-

pended claims as it is to be clearly understood that variations and modifications which properly fall within the scope of said claims may be resorted to when found expedient.

In the drawings—

Figure 1 is a perspective view of a shoe sole constructed in accordance with the invention and illustrating the portions thereof in separated condition for receiving and securing the lining therebetween.

Fig. 2 is a cross sectional view therethrough prior to the separation of the portions thereof and the application of the lining thereto.

Fig. 3 is a cross sectional view of the improved sole in applied position in a completed shoe.

Referring to the drawings by characters of reference the improved sole constituting the present invention comprises a body 10 formed with an integral relatively thin marginal flange or welt portion 11 projecting outwardly from the lower portion thereof and extending around the shank and forepart thereof. From a point adjacent to or slightly spaced from the rear ends of the flange or welt portion 11, the body is slotted inwardly and downwardly at an angle to intersect the lower surface or bottom 12 of the body thereby providing the flange or welt portion 11 with an inwardly projecting integral rand portion 13 having a skived upper edge 14 adapted to underlie the marginal edge of the body, the said body being provided with a complementary skived marginal edge 15 extending around the shank and forepart and permitting of relative separation of the body and flange or welt portion and rand as illustrated in Fig. 1. In manufacturing a shoe, the lining A of the upper B has its edges C turned inwardly and secured preferably by cementing between the complementary skived edges 14 and 15 while the free edge D of the upper is turned outwardly and secured by stapling stitches or other means E to the flange or welt portion 11. The outsole F is applied to the under side of the body 10 and a mock welt G may if desired be applied over the outturned edges D of the upper after which the said mock welt G, outturned edge D

of the upper, flange or welt portion 11 and outsole F are stitched together by the stitching H. By separating the skived edges 14 and 15 of the rand and body 10 of the sole, 5 it is obvious that the operation of inserting and securing the lining edges C therebetween is greatly facilitated, admits of a smoother finish and at the same time minimizes the time and labor required for such 10 operation.

From the foregoing it is obvious that the following are among the many advantages derived from the construction, namely: (1) the integrally connected or permanently 15 united insole and combined rand and welt facilitates the proper registration and relation of said parts during the process of handling and in the use of them in the making of a shoe; (2) the combined rand and welt will, due to its integral construction, be of a size required by the size of the insole and outsole with which it is used and of which it forms an integral part, thus 20 obviating the necessity of selecting from a large number of separately formed rands and welts, a particular size to fit a particular sole; (3) the formation of the rand, 25 welt and insole integral permits the production by a single cutting operation of the under side bevel about the margin of the shank and forepart of the insole and the corresponding bevel of the rand projecting beneath the sole, thus producing mating, 30 complementary beveled surfaces between 35 which the lining is secured.

It is, of course, to be understood that the blank from which the insole is made, is formed exactly to the size of the heel at its rear portion to produce a heel seat and 40 that it is laterally enlarged from a point corresponding to the front of the heel, along the shank and about the forepart to produce the projecting welt portion or flange. Thereafter the edge of the projecting portion 45 is slit inwardly parallel to the upper and under surfaces about the shank and forepart upon a line corresponding to the marginal edge of the shank and forepart of the insole and that the upper part of this 50 extension formed by slitting is removed by a cut substantially triangular to the surface, thus forming a shoulder defining the shank and forepart of the insole and that part extending beyond the shoulder 55 which constitutes the welt. Thereafter the rand portion is formed by a cut which extends inwardly at an angle from the base of this shoulder to the under surface producing both the under beveled marginal 60 edge of the insole and the upper beveled edge of the rand portion of the welt or flange.

I claim:

1. An insole for "stitch-down" shoe structures, comprising a body including a heel 65

portion, a shank and forepart, an integral outwardly projecting welt secured to the opposite sides of the shank adjacent its juncture with the front of the heel portion and extending around the shank and forepart and a rand extending inwardly from and formed integral with the welt to normally underlie the marginal portion of the shank and forepart. 70

2. An insole for "stitch-down" shoe structures, comprising a body including a heel portion, a shank and forepart, an integral outwardly projecting welt secured to the opposite sides of the shank adjacent its junction with the front of the heel portion and extending around the shank and forepart and a rand extending inwardly from and formed integral with the welt to normally underlie the marginal portion of the shank and forepart, the said marginal portion of 80 the shank and forepart and confronting face of the rand being complementarily skived. 85

3. An insole for shoes comprising a body member having a reduced outwardly projecting flange or rand from the lower portion of the marginal edge of the shank and forepart, the said body being slotted inwardly and downwardly from its juncture with the flange or rand from a point adjacent the rear edges of the rand to provide 90 complementary skived faces permitting of 95 relative separation.

4. A "stitch-down" shoe, comprising an insole and a combined rand and welt formed integrally and permanently connected at a point approximating the front of the heel seat, the combined rand and welt extending along the shank and about the forepart, with the rand portion extending beneath the 100 marginal edge of the shank and forepart of the insole, the whole formed of a single piece of leather, the opposed surfaces of the insole and rand beveled by an inclined cut extending from the edge of the insole to a 105 point within the edge and emerging from the under surface thereof, a lining turned inwardly and secured between the opposed beveled surfaces of the insole and rand, an upper having its edge turned outwardly 110 upon the upper surface of the welt, means for fastening the upper to the welt on a line closely adjacent the edge of the insole, and an outsole secured to the outstanding welt portion of the combined rand and welt. 115

5. A combined insole, rand and welt, having a projecting edge forming the welt along the shank and about the forepart from a point approximating the front of the heel seat and formed integrally of a single piece 120 of leather, and a rand portion extending inwardly from the edge of the insole beneath the under surface thereof, the insole and rand having opposed complementary beveled surfaces. 125

6. In a shoe, an inner sole consisting of a body formed with a marginal projecting flange extending around the shank and forepart at the lower portion thereof and slitted from the juncture of the upper face of the flange transversely inward and downward through the bottom to permit of relative

separation of the flange and body for facilitating the insertion and securement of the lining therebetween, the flange constituting means for securing the upper to the insole and means for attaching the welt and outsole to the insole and upper.
